AUTOMATIC VARIABLE PITCH PROPELLER

Robert L. Kelm, Lake View, N. Y.

Application November 8, 1932, Serial No. 641,725

3 Claims. (Cl. 170—162)

This invention relates to an automatically variable pitch propeller which is more particularly intended for use in propelling aeroplanes. As is well-known to operators of aeroplanes considerably more power is required to lift the aeroplane from the ground than is required for propelling the same through the air after the same has been elevated. For example, an engine after starting from a standstill may run 2400 revolutions per minute by the time the aeroplane is lifted but when in the air 1600 revolutions per minute will suffice to continue its propulsion assuming that the pitch of the propeller is fixed.

It is also well-known that a propeller having its blade arranged at a small pitch exerts a more powerful grip on the air than one having its blades pitch at a relatively great angle.

This invention proposes utilizing this action advantageously by providing a propeller having 20 blades capable of being adjusted as to their pitch or angularity relative to the plane of rotation and automatically actuating said blades so that the same when standing still or rotating at low speed will be arranged at a relatively great pitch 25 or angle, but when running at high speed will be arranged at a small pitch or angle. As a result the aeroplane can be lifted very easily and quickly from the ground by running the engine at a high speed while the propeller blades are 30 at a small pitch, and when the aeroplane is off the ground the speed of the engine can be reduced to avoid unnecessary wear and expenditure of power but still propel the aeroplane with ease while the blades assume a position of greater angularity or pitch.

It is the purpose of this invention to provide a propeller which is capable of performing this function by simple, efficient and reliable means which operate to automatically turn the blades 40 by centrifugal force from one of high angularity or pitch to one of low angularity or pitch as the speed of the engine increases, and to return the blades by spring means from a position of low pitch or angularity as the speed of the engine 45 is reduced, thereby securing uniformity of action and reducing the cost of maintenance.

In the accompanying drawing:

Figure 1 is a front elevation, on a reduced scale, of an aeroplane propeller embodying my 50 invention and showing the parts in the position which they occupy when the propeller is at rest.

Figure 2 is a fragmentary longitudinal section of the propeller on an enlarged scale.

Figures 3 and 4 are transverse sections of the 55 same taken on the correspondingly numbered lines in Fig. 2.

In the following description similar characters of reference indicate like parts in the several figures of the drawing.

60 Referring to the drawing, the numeral 10

represents the rotatable member of the motor which is adapted to drive the propeller, such for example as the horizontal crank or driving shaft of the gas engine of a kind now commonly employed for propelling aeroplanes.

65

Upon the end of this driving or power shaft is mounted the variable pitch propeller which embodies my invention and which in its preferred form is constructed as follows:

The numeral 11 represents a hub preferably 70 of cylindrical form secured to the end of the driving shaft by means of a key 12, as shown in Figs. 1, 2 and 4, or by any other suitable means.

From this hub a plurality of guide tubes 13 75 extend radially, two of such tubes being shown in Figs. 1 and 2 arranged on diametrically opposite sides of the hub. Adjacent to the outer ends of these guide tubes are arranged propeller blades 14 which may be of any suitable construction and trend in opposite directions, so far as the angularity of their front faces or working surfaces are concerned, in a manner common to propeller blades of this type.

Each of these propeller blades is provided at 85 its inner end with a cylindrical shank 15 which is arranged concentrically within the adjacent guide tube and is capable of both a longitudinal and also a rotary motion relative to said tube.

At its inner end each shank 15 is provided with 90 a supporting collar 16 preferably of circular form, which collar is preferably rigidly secured to the respective shank so as to be compelled to move lengthwise and also rotate therewith. The preferred means for accomplishing this consists of 95 a square or flat sided neck 17 arranged at the inner end of the shank 15 and engaging with a correspondingly shaped opening 18 in the center of the collar 16, and a screw nut 19 engaging with the inner side of the supporting collar 16 and 100 mounted on a screw threaded stem 20 which projects inwardly from the respective neck 17. Unscrewing of this nut due to vibration of the propeller is prevented by providing this nut with a plurality of radial notches 21 so that the same 105 is of castellated form and engaging a pair of diametrically opposite notches by means of a cotter pin 22 extending through the adjacent part of the stem 20, as shown in Fig. 2.

The inner end of each shank is guided in the 110 bore of the respective guide tube so as to be capable of reciprocating lengthwise therein and also rotating about the axis of the shank and tube, this being accomplished in the present instance by means of a ball bearing comprising an 115 inner bearing ring 23, an outer bearing ring 24, and an annular row of balls 25 interposed between ball races 26, 27 formed on the opposite sides of the bearing rings 23 and 24, as shown in Fig. 2. Each of these bearing rings engages its 120

bore and periphery with the outer side of the shank 15 and the inner side of the guide tube, and the inner ring additionally engages its rear lateral side with the front side of the supporting 5 collar 16.

During the operation of this propeller this ball bearing unit moves lengthwise with the shank in the guide tube which is radial with reference to the axis of rotation of the driving 10 shaft 10, and these bearing rings are also free to rotate one relatively to the other about the axis of the shank and guide tube, the friction of which movement is reduced to a minimum due to the presence of the balls 25 between these bearing 15 rings, thereby enabling these movements to be effected easily and without undue wear.

The outer part of the shank of each blade is mounted on the outer part of the respective guide tube by means of a bearing which permits the 20 shank to rotate and also slide relative to the adjacent part of the guide tube, which bearing comprises inner and outer bearing rings 28, 29, and an annular row of balls 30 interposed between the ball races 31, 32 which are formed on 25 the opposing surfaces of these bearing rings. The inner bearing ring 28 engages with the periphery of the shank 15 and the outer bearing ring 29 bears with its periphery against the bore 33 of an outer supporting ring 34, while the rear 30 side of this last-mentioned bearing ring engages with an outwardly facing shoulder 35 on this supporting ring.

The periphery of this last-mentioned supporting 35 ring engages with a bore 36 of a cylindrical enlargement at the outer end of the respective guide tube, and the rear side of this supporting ring engages with an outwardly or forwardly facing shoulder 37 at the inner end of the enlarged bore 36, as shown in Fig. 2.

40 The outer supporting ring 34 is held in place on the respective guide tube and the two bearing rings 28 and 29 of the front ball bearing are held in place within the outer supporting ring 34 by a screw cap, the crown 38 of which engages the 45 front ends of the bearing rings 28, 29 while the flange 39 thereof is connected by means of a screw joint 40 with the outer end of the respective guide tube, as shown in Fig. 2.

40 The shank 15 of each propeller blade is yieldingly held in its innermost position radially by 50 means of a return spring 41 which surrounds the shank within the guide tube and bears at its inner end against the front ring 24 of the rear ball bearing, while the outer end of this spring 55 bears against the inner side of the outer supporting ring 34 for the purpose of causing the rotary sliding movement of the shank and the parts associated therewith to be effected without binding, the interior of the guide tube is filled with 60 a lubricant and escape of the latter from the guide tube is prevented by means of a circular packing 42 surrounding the outer part of the shank and seated in an annular groove 43 of a flange 44 on the outer side of the crown 38 of the 65 retaining cap.

Means are provided whereby, upon moving the shank blade and associated parts radially outward relative to the axis of the driving shaft, this blade will be automatically turned by centrifugal 70 force so that it will be shifted from a position in which the blade is arranged at a great angle relative to the plane of rotation into a position in which the blade assumes a small angularity or pitch relatively to this plane, and when the propeller ceases to rotate each propeller blade will 75

be turned back from a position of small angularity to one of great angularity relative to the plane of rotation.

The means for this purpose preferably consist of a shifting pin 45 secured to the periphery of the supporting collar 16 and engaging with a helical or cam slot 46 formed in the adjacent part of the guide tube, as shown in Figs. 1 and 3.

80 The cap at the outer end of each guide tube is prevented from unscrewing due to vibration of the propeller by means of a nut lock which preferably consists of a ring 47 engaging with the inner end of the flange of each cap and provided with a plurality of prongs 48 engaging with an annular external groove 49 and flat faces 52 on the periphery of the flange of this cap, and an inner prong 50 which is bent into a notch 51 on the adjacent screw threaded part of the guide tube after the cap has been tightened on the respective guide tube. By thus preventing the cap from unscrewing, the several parts constituting the means for mounting each blade on the respective guide tube are reliably held in their assembled position and thus insure proper operation of the propeller at all times.

90 When the propeller of the aeroplane is at rest the shanks of the blades are in their innermost radial positions within the guide tubes, and the shanks and blades are turned about their radial axes through the medium of the helical or cam 95 slots 46 operating upon the shifting pins 45 so that the blades are arranged at the greatest angularity or angle of incidence relative to the plane of rotation of the blades. The blades, shanks, and associated parts moving therewith are 100 yieldingly retained in this position by the springs 41, and the extent of the inward movement of these shanks and the backward rotation of the blades is limited by engagement of the shifting pins with the rear ends of the helical 105 or cam slots 46, as shown in Fig. 1.

Upon starting the rotation of the propeller while the parts are in this position a maximum 110 of air resistance is encountered by the blades inasmuch as the angle of incidence of the blades 115 at this time is the highest.

As the speed of the propeller increases, the 120 centrifugal force exerted upon the blades due to this speed causes the blades, shanks and associated parts to be thrown radially outward and the 125 springs 41 to be compressed. At the same time the shifting pins 45 acting upon the helical or cam slots 46 during this outward movement of the shanks and blades, will cause the shanks and 130 blades to be turned about their radial axes so that when these pins reach the outer ends of these slots the blades have been turned about their radial axes into a position in which they present the lowest pitch or angle of incidence of their front or advancing surfaces to the plane of rotation, and thereby correspondingly increase the 135 grip of the blades on the air and the propelling effect of the same.

In practice the engine is run at high speed and with the blades of the propeller at their greatest 140 pitch or angularity only during the time the plane is being lifted from the ground and then the speed of the engine is reduced to normal running, and when this occurs the reduction in the centrifugal force on the blades permits the springs 145 41 to draw the blade radially inwardly, and the shifting pins 45 and cam slots 46 to turn the blades into a position in which the pitch or angularity of the same is increased to the maximum, whereby the plane is propelled in the air at an 150

increased speed while the engine is running at a reduced speed.

By this means the motor may be operated at a high initial speed with the blades of the propeller at a comparatively low pitch which permits quick lifting of the plane, and after the plane has been lifted the speed of the motor is reduced and the angularity of the blades is automatically changed to one in which a greater grip of the blades is

10 obtained on the air for the purpose of obtaining the maximum propelling effect of the propeller.

As a result of this the aeroplane will be lifted from the ground positively and promptly and with greater ease and smoothness of action than has been possible heretofore by a relatively high speed of the engine and then propelled in the air at a high speed while the speed of the engine is reduced, thereby insuring better control of the aeroplane and greater safety in its operation. From the foregoing explanation it will now be clear that the supporting ring 34 engages with the outwardly facing shoulder 37 on the radial guide tube 13, and this supporting ring is itself provided with another internal outwardly facing shoulder 35 on which a ball bearing is seated and provides means in which the shank 15 of the propeller blade slides and turns, this ball bearing being engaged by a cap which is connected with said tube for holding the bearing in place.

30 The mechanism whereby this is accomplished is comparatively simple and compact in construction, and its several parts are so organized that the same are not liable to be injured or get out of order, and they are also readily accessible for inspection, adjustment and repairing.

I claim as my invention:—

1. An automatic variable pitch propeller comprising a hub adapted to be mounted on a rotating driving member and having a radial guide tube, a propeller blade having a radial shank movable lengthwise in said tube, said tube provided at its outer end with an outwardly facing shoulder and in its side with a helical slot, a supporting ring engaging said shoulder and itself provided with another internal outwardly facing shoulder, a

ball bearing which is seated on the shoulder of said ring and in which said shank slides and turns, a cap engaging said ball bearing and connected with said tube, a collar secured to the inner end of said shank, a spring interposed between said collar and supporting ring, and a pin projecting laterally from said collar and engaging with said helical slot.

2. An automatic variable pitch propeller comprising a hub adapted to be mounted on a rotating driving member and having a radial guide tube, a propeller blade having a radial shank movable lengthwise in said tube, said tube provided at its outer end with an outwardly facing shoulder and in its side with a helical slot, a supporting ring engaging said shoulder and itself provided with another internal outwardly facing shoulder, a ball bearing which is seated on the shoulder of said ring, and in which said shank slides and turns, a cap engaging said ball bearing and connected with said tube, a flat sided neck at the inner end of said shank, a collar having a flat sided bore engaging said neck, a pin projecting from said collar into said slot, and a spring interposed between said collar and ring.

3. An automatic variable pitch propeller comprising a hub adapted to be mounted on a rotating driving member and having a radial guide tube, a propeller blade having a radial shank movable lengthwise in said tube, said tube provided at its outer end with an outwardly facing shoulder and in its side with a helical slot, a supporting ring engaging said shoulder and itself provided with another internal outwardly facing shoulder, a ball bearing which is seated on the shoulder of said ring, and in which said shank slides and turns, a cap engaging said ball bearing and connected with said tube, a collar secured to the inner end of said shank, a spring interposed between said collar and supporting ring, a pin projecting laterally from said collar and engaging with said helical slot, and a packing mounted on said cap and surrounding said shank.
